(57) **CLAIM**

The ornamental design for a connector device, as shown and described.

DESCRIPTION

FIG. 1 is a perspective view of a connector device showing our new design;

FIG. 2 is a rear perspective view thereof;

FIG. 3 is a left plan view thereof;

FIG. 4 is a bottom plan view thereof;

FIG. 5 is a right plan view thereof;

FIG. 6 is another left plan view thereof;

FIG. 7 is a top plan view thereof; and,

FIG. 8 is another right plan view thereof.

The portions that would be visible behind a transparent or translucent surface are omitted for a clear disclosure of the surface configuration. No claim is made to any element inside or behind the transparent or translucent surface. Appendix images A1-A8 are 3D view renderings of a connector device portraying the claimed design.
